UNITED STATES PATENT OFFICE.

ELIZABETH MILLER AND CELESTINE BARTON, OF BROOKLYN, NEW YORK.

DESIGN FOR TRIMMING.

SPECIFICATION forming part of Design No. 22,494, dated June 6, 1893

Application filed March 24, 1893. Serial No. 467,508. Term of patent 7 years.

To all whom it may concern:

Be it known that we, ELIZABETH MILLER and CELESTINE BARTON, citizens of the United States, residing at Brooklyn, Kings county, New York, have invented and produced a new and original Design for Ruching and Trimming, of which the following is a specification, reference being had to the accompanying drawing, showing a part thereof, and which

5 o represents a face view of a piece of our newly-designed ruching or trimming.

The leading feature of our design consists of a strip of ruching or trimming the upper edge of which is straddled by a series of parallel transverse arches, each composed of a set 5 of beads that extend for some distance down along the face of the fabric.

a represents a strip of knitted ruching or trimming, the upper edge of which is straddled by the transverse parallel arches. Each 20 of these arches is composed of a set of beads b, that extend for some distance down along the face of the strip a. Moreover the arches are not set at right angles to the strip a but they are inclined slightly, so as to be fully exposed and to produce a full and rich effect. 25

What we claim is—

The design for ruching and trimming, substantially as shown and described.

ELIZABETH MILLER.
CELESTINE BARTON.
